Drawn No. 310.—
John C. Merchant—

Design for three Dishes after 1. 180.—

Silas Merchant, of Cleveland, Ohio.
Letters Patent No. 410. Dated, Sept 2nd 1851.

The Schedule referred to in these Letters Patent and making part of the same.

To all whom it may concern:

Be it known that I, S. Merchant of the city of Cleveland, in the county of Cuyahoga, and state of Ohio, have invented or produced a new and original design or ornaments for the doors of a cooking stove, and I do hereby declare that the following is a full & exact description of the same - reference being had to the accompanying drawings making part of this specification.

Fig 1, perspective view of my stove.

Fig 2, view of the fire place door.

Fig 3, view of the upper oven door.

Fig 4, view of the lower oven door.

Fig 5, side view of the stove.

The side plate fig 5, occupies the same place in the stove as the plate A in fig 1. the fire door place B, is fig 5, is for the door fig 2, the door fig 3 is for the upper oven c in fig 5, the door fig 4, is also attached to the lower oven D, the side plate fig 5, & the doors fig 2, fig 3, and fig 4, have the relative place in the stove with the same form & configuration as the side plate A, and doors E, F and G in fig 1. In the panel of the door fig 4, are placed basso relief ornaments H, which is surrounded by the following described mouldings.

The ovoli I, with the bead K, at the foot. The ovoli I is surrounded by the coor M, and fillet N, which is surmounted by the astrical O. The style and configuration of these mouldings & ornaments of this door fig 4, corresponds to the door G in fig 1.

The basso relief scroll P in the panel of the door fig 3, is also surrounded by the mouldings R, S, T, U, and V, which are the same in form and arrangement as the mouldings K, I, O, M and N, described in fig 4, and corresponds in form & configuration to the ^{door} E, in fig 1. The basso relief rosette A, in fig 2, is also surrounded by mouldings as seen at B, C, D, E and F, which are the same in form as in the door fig 3, and also being the same as before described in the door fig 4, the door fig 2, in form & configuration correspond in place with the door E in fig 1.

I disclaim the hearth W in fig 1, and the projection I in fig 2,

But what I do claim as my design & production and desire to secure by Letter Patent is the Basso relief ornaments, form and configuration of the doors E, F, and G, in fig 1, which are substantially the same as ^{and} before described in the doors fig 2, fig 3, and fig 4.
